(57) **CLAIM**

We claim the ornamental design for front portions of the housing of a handle and housing assembly, as shown and described.

DESCRIPTION

FIG. 1 is a perspective view showing mainly front, left and large rounded end features of our new design;

FIG. 2 is a front view thereof;

FIG. 3 is a left side view thereof, it being understood that a right side view is identical hereto but a mirror image reversal hereof;

FIG. 4 is a large rounded end view thereof;

FIG. 5 is an opposite end view thereof; and,

FIG. 6 is a perspective view thereof looking into the interior of the smaller end thereof so shallow end region features thereof can be more clearly seen.

The broken line disclosure in several of the views of other features is provided for illustrative purposes only and forms no part of the claimed design.

The broken lines are included for the purpose of illustration and form no part of the claimed design.
